SCREW HOLDING SCREW DRIVER
ATTACHMENT

Maximilian C. Becker, East Orange, N. J.

Application July 15, 1948, Serial No. 38,790

2 Claims. (Cl. 145—52)

1

This invention relates to tools of the screw driver type having as part thereof an attachment for holding a screw. In another of its aspects the invention is directed to a novel attachment for screw drivers, which attachment is efficient in operation, cheap to manufacture, may be readily combined with conventional type screw drivers and releasably maintains a screw in position.

The various advantages and objects of this invention will be readily apparent from the following description taken in connection with the appended drawings, wherein:

Fig. 1 is a top plan view of a blank of a springy sheet metal band or strip after the stamping operation and before bending.

Fig. 2 is a perspective view of the stamped or cut out band shown in Fig. 1 but after the bending operation.

Fig. 3 is a perspective view of an assembly of a conventional screw driver with the attachment shown in Fig. 2.

Fig. 4 is a perspective view of a modification of the attachment shown in Fig. 2.

Fig. 5 is a view similar to Fig. 3, but with the attachment shown in Fig. 4 combined with a conventional screw driver, instead of that shown in Fig. 2.

As shown in the drawings, the novel attachment may comprise a flat spring sheet metal band or strip 10 having an elongated recess 11 at one end thereof and a pair of spaced openings 12 and 13. The recess 11 may consist of an outwardly diverging receiving mouth 14 communicating with a receiving slot 15 in turn communicating with a generally arcuate opening 16 whose diameter is greater than the width of the slot 15. A narrow slot or slit 17 extends from the arcuate opening 16 and terminates in an arcuate opening 18 whose diameter is greater than that of slot 17.

The slotted or recessed end of the band 10 is bent widthwise upwardly on a line between the arcuate openings 16 and 18 and is at approximately right angles to that portion of band 10 adjacent thereto to provide a screw or bolt receiving and holding element 20. The recess 11 in the end of the band 10 provides an elongated bifurcation with the arms 21 and 22 thereof being resilient and capable of being movable outwardly widthwise with respect to each other.

The openings 12 and 13 are preferably elongated and may be of any desirable width depending upon the dimension of the screw driver employed. The width of each opening 12 and 13 is preferably greater than the diameter of a

5 shank of a screw driver to be coupled with band 10 and its length is greater than the maximum widthwise dimension of the operating end of a screw driver. The band 10 may be bent widthwise at 19 between the openings 18 and 12 if desired.

As shown in Fig. 3 in which a conventional screw driver is illustrated, the driver consists of a handle 23 and an elongated shank 24 secured thereto and extending from one end thereof. The shank 24 has a screw engaging head 25 terminating at its free end in a knife edge. The free end head 25 may be of any desirable contour for the purpose of gripping or engaging screws of any of the well-known types and need not be a knife edge, shown merely for the purpose of illustrating the invention herein.

The attachment shown in Fig. 2 may be readily and easily combined with the screw driver in the following manner; the knife edge is inserted first through the opening 13 and pushed forward until it is located adjacent the opening 12, whereupon pressure is applied to the forward end of the band 10 to locate part of the opening 13 below the lower end of the knife edge 25. Then the driver is pushed forwardly through opening 12 until the operating end thereof is located adjacent to the bent up portion 20. In this combination the rear portion of the band 10 makes frictional contact with the shank of the driver to maintain the attachment in position on said shank. In operation the threaded or shank end of a screw 50 may be inserted through the mouth 14 into receiving slot 15, whereupon arms 21 and 22 spring away from each other during insertion; and into the arcuate opening 16, whereupon arms 21 and 22 spring towards each other to releasably maintain in position the screw 50. After the screw is located in position and maintained in said position by virtue of the resilient fingers 21 and 22, the driver may be pushed forwardly and its knife end 25 is inserted into the slot normally present on the head of the screw 50. When the attachment is not needed the attachment may be pushed rearwardly towards the handle whereby the shank of the driver is located in the arcuate opening 16 and is maintained in inoperative position by frictional engagement as shown in dotted lines in Fig. 3.

Another embodiment of my invention is shown in Fig. 4 and consists of a single piece of wire which may be twisted to provide a pair of spaced openings 30 and 31 at one end and a pair of spaced wire elements 32 and 33 at the other end and at right angles to the adjacent part thereof.

The free ends 32 and 33 may be in arcuate form terminating in outwardly flared extremities 34 providing a receiving mouth 35 and a narrow receiving slot 36.

While the invention has been described in detail, it is not to be limited thereby, because it is subject to various changes and modifications.

I claim:

1. An attachment for a screw driver including a shank and a screw head engaging end, being an elongated sheet metal member, one portion having a pair of openings through the thickness thereof through which said screw head engaging end may pass and said shank may extend to become in frictional engagement with parts of the edges of said member defining said openings for maintaining said member in operative position on said shank, the other portion of said member having a pair of openings through the thickness thereof, a slot extending through the free end of said other portion to one of said second mentioned pair of openings and a slot extending between said second mentioned pair of openings, both of said slots being through the thickness of said member, the free end of said other portion being at approximately right angles to the remainder of said portion and being in the form of spaced fingers movable relative to each other for screw insertion.

2. An attachment for a screw driver including a shank and a screw head engaging end, being an elongated resilient member of sheet material, one portion having a pair of openings through the thickness thereof through which said screw

head engaging end may pass and said shank may extend to become in frictional engagement with parts of the edges of said member defining said openings for maintaining said member in operative position on said shank, the other portion of said member having a slot through the thickness thereof extending through and beyond the free end thereof, the free end of said other portion being at approximately right angles to the remainder of said portion and being in the form of spaced fingers movable relative to each other for screw insertion.

MAXIMILIAN C. BECKER.
